CLAIM

I claim the ornamental design for a blanket convertible to a bag, as shown and described.

DESCRIPTION

FIG. 1. is a perspective view of blanket convertible to a bag showing the design in an open configuration.

FIG. 2. is a top view thereof.

FIG. 3. is a bottom view thereof.

FIG. 4. is a left side view thereof.

FIG. 5. is a right side view thereof.

FIG. 6. is a rear view thereof.

FIG. 7. is a front view thereof.

FIG. 8. is a top perspective view of the blanket convertible to a bag of FIG. 1 in a first alternate configuration with the squared corners rolled to the center.

FIG. 9. is a bottom view of the blanket convertible to a bag of FIG. 1 in a second alternate configuration.

FIG. 10. is a top perspective view of the blanket convertible to a bag of FIG. 1 in a third alternate configuration with the squared corners rolled to the center and folded; and,

FIG. 11. is a top perspective view of the blanket convertible to a bag of FIG. 1 in a fourth alternate configuration and closed position.

1 Claim, 8 Drawing Sheets
